UNITED STATES PATENT OFFICE.

GEORGE C. WRIGHT, OF NEW YORK, N. Y., ASSIGNOR TO E. S. HIGGINS & CO., OF SAME PLACE.

DESIGN FOR A CARPET-PATTERN.

Specification forming part of Design No. 5,604, dated March 5, 1872.

Specification describing a Design for Carpets, invented by GEO. C. WRIGHT, of New York, county of New York and State of New York.

The nature of my design is fully represented in the accompanying photographic illustration, to which reference is made.

A and B are figures of similar construction, formed by continuous bands running over and under each other, producing, also, small square figures between A and B. The corners of figure A are surmounted with scrolls in the form of a lyre, which projects over the border onto the ground C. Near the corner of figure B is a scroll radiating toward the matching-point D. Upon the centers of A and B are figures E E, conforming to the general style of design. I prefer to color A scarlet; B, green; bands, brown, (outlined with gold;) ground, drab,

(with suitable figures, moss-work, &c., thereon.) I do not consider the coloring selected an essential element of my design. I am aware that carpet-patterns composed of bands that form two distinct centers and side figures are not new, and lay no claim to that feature. The distinctive character of my design is found in the style and combination of figures which are produced by the bands, scrolls, leaves, and stems.

What I claim as my invention is—

A design for carpets composed of figures, formed substantially in the manner above described.

GEORGE C. WRIGHT.
